UNITED STATES PATENT OFFICE

120,770

DESIGN FOR A COMBINED NAIL POLISH DISPLAY AND STAND

James L. Younghusband, Chicago, Ill.

Application March 5, 1940, Serial No. 90,701

Term of patent 7 years

To all whom it may concern:

Be it known that I, James L. Younghusband, a citizen of the Dominion of Canada, residing at 30 West Hubbard Street, Chicago, Illinois, have invented a new, original, and ornamental Design for a Combined Nail Polish Display and Stand, of which the following is a specification, reference being had to the accompanying drawing, forming a part thereof.

Fig. 1 is a front elevational view of a combined nail polish display and stand, showing my new design, which is the same on both the front and the back, and Fig. 2 is a top plan view of the same.

I claim:

The ornamental design for a combined nail polish display and stand, substantially as shown and described.

JAMES L. YOUNGHUSBAND.
